TWISTING AND WINDING APPARATUS

Franklin H. Shinn, Norwood, N. C.

Application September 21, 1934, Serial No. 744,946

11 Claims. (Cl. 117—49)

This invention relates to a combined twister and packaging machine whereby the fliers impart two turns per revolution to the yarn being wound thereon, and is so designed as to stand in a vertical position and therefore being capable of being mounted on a conventional twisting frame, roving frame and the like by the simple addition of a top bolster rail.

It is an object of this invention to provide a combined twisting and packaging machine for yarns wherein the yarn can be passed from the drafting rolls in fiber preparation machinery twice as fast as in a twisting machine employing ring twisting because ring twisting imparts only one turn or twist per revolution whereas the present invention imparts two turns per revolution to the yarn being not only twisted, but packaged at the same operation.

It is another object of this invention to provide an apparatus adapted to be associated with fiber preparation machinery which will wind and twist the yarn in one operation and which is applicable to roving frames, spinning frames, twisting frames and the like, the spooling operation being eliminated as the yarn is twisted and placed on proper yarn holders such as tubes, spools and the like, at the same operation, and the apparatus is applicable to roving frames, spinning frames, twisting frames and the like, since it takes the yarn directly from the drafting rolls of these frames and twists the same and packages it at one operation.

Some of the objects of the invention having been stated, other objects will appear as the description proceeds when taken in connection with the accompanying drawings, in which:—

Figure 1 is a vertical sectional view of my invention applied to a twisting spindle and showing portions in elevation; Figure 2 is a vertical sectional view looking at the left-hand portion of Figure 1 and showing the flier in a different position;

Figure 3 is a sectional plan view taken along line 3—3 in Figure 2;

Figure 4 is a vertical sectional view taken along line 4—4 in Figure 1;

Figure 5 is an isometric view of a portion of the locking device for holding the spool rack in stationary position;

Figure 6 is an isometric view of the lower portion of the locking device for holding the spool rack in stationary position.

Referring more specifically to the drawings, the numeral 10 denotes the lower rail of a twister which has mounted therein a flanged bolster 11, this bolster being secured to the rail 10 by any suitable means such as nut 12 disposed beneath the rail. Bolster 11 has rotatably mounted therein a spindle which

whorl 13. Fixedly secured to the upper portion of whorl 13 is a lower flier 14 which comprises member 15 and a counter weight member 16. Member 15 extends upwardly and is forked at its upper end.

Secured as at 17 to one of the forked members is a flexible member 18 which is composed of any flexible material such as rubber tubing and the like and secured to the upper end of member 18 as at 19 is arm 20 of the upper flier 21, said upper flier 21 having a counter weight arm 22 integral therewith disposed on the opposite side of the pivot point from member 20. The upper flier 21 has a spindle 28 which is rotatably mounted in bearing 29 which bearing is secured in top rail 30. Fixedly secured on the upper end of spindle 28 is another whorl 31 which is adapted to be driven by the same cylinder that drives the lower whorl 13.

The lower portion of flier 14 has projecting upwardly from the central portion thereof, a collar 32, around which is mounted a suitable radial thrust bearing 33 and on top of which is mounted an end thrust bearing 34. The outer ring of bearing 33 is secured to the lower portion of spool rack 35 and allows the flier 14 to rotate while the spool rack remains stationary.

End thrust bearing 34 assumes the weight of the spool rack as the flier 14 rotates. Spool rack 35 has two arms 36 and 37 which extend upwardly and then again laterally and are joined together again at the hub portion 38. Fixedly secured in hub 38, by any suitable means such as set screw 40 is a vertically disposed rod 39. The upper end of member 39 is forked and has two projections 41 and 42 which are adapted to fit into cavities 43 and 44 respectively of locking device 45. Member 45 has integral therewith an upwardly projecting member 46 which is adapted to fit into the central portion of spindle 28. By referring to Figure 1 it is seen that the spindles in bolster 11 and the member 39 are in direct alignment whereas, the spindle 28 which is rotatably mounted in the top rail 30 is off-center. Since the spool rack 35 remains stationary at all times, and the fliers 14 and 21 are constantly rotating, the resilient member 18 must be provided because the fliers 14 and 21 rotate about two different centers, in other words, the two fliers are not concentric.

By placing the upper spindle 28 off-center from the lower spindle, and providing locking member 39 with prongs 41 and 42 thereon which fit into the second locking member 45, it is impossible for the spool rack 35 to rotate and it is thereby held in stationary position at all times, regardless of the speed of the fliers 14 and 21.

The upper end of member 15 has a prong 53 which extends upwardly and laterally and has integral with the end thereof a collar 54, said col-

lar 54 being adapted to rotate around the lower portion of member 39. This collar 54 also has a spiral gear 55 cut therein which is adapted to mesh with a pinion 56, said pinion 56 being fixedly secured on shaft 57. The shaft 57 has one end rotatably mounted in housing 58 and its other end rotatably mounted in the cover 59 which is secured to housing 58 by any suitable means such as screws 60. Pinion 56 also meshes with another pinion 61 which, in turn, is fixedly secured on shaft 62, said shaft 62 being also rotatably mounted in housing 58 and cover 59. A beveled gear 63 is fixedly secured on shaft 62 which meshes with a second beveled gear 64 fixedly secured on shaft 65, said shaft 65 being rotatably mounted in a bearing 66 which is integral with the housing 58 and another bearing 68 which is integral with the upper portion of spool rack 35. The housing 58 encloses the gears 55, 56, 61, 63 and 64 and normally rests on the top of spool rack 35 and is secured thereto by any suitable means such as stud bolts 69.

Fixedly mounted on the end of shaft 65 is a worm gear 76 which meshes with a pinion 77. Pinion 77 is fixedly mounted on the upper end of shaft 78 which shaft is rotatably mounted in bearings 79 and 80 which are integral with member 36 of spool rack 35.

The lower end of shaft 78 has fixedly secured thereon a beveled gear 81 which meshes with another beveled gear 82, said beveled gear 82 being fixedly secured on one end of roller 83. Roller 83 has its ends rotatably mounted in members 36 and 37 of spool rack 35, and a tube of yarn 84 normally contacts this roller and is rotated thereby. The tube of yarn 84 is rotatably mounted on a transverse shaft 85 which is slidably mounted in slots 86 and 87 cut in vertically disposed members 36 and 37 respectively. These slots are identical in all respects and a showing of one is deemed sufficient. (See Fig. 2.)

One end of shaft 85 has a tension spring 88 secured thereto which extends downwardly and is secured to member 35 as at 89. The other end of shaft 85 has a similar spring 90 secured thereto which also extends downwardly and is secured as at 91 to vertically disposed member 37. It is seen that these springs normally pull the shaft 85 and the tube of yarn 84, which is rotatably mounted therein, downwardly in contact with the roller 83 at all times and as the roller 83 is rotated the tube of yarn 84 will also be rotated to cause the yarn to be wound on the spool at a uniform rate.

Beveled gear 82 also meshes with another beveled gear 92 which is fixedly secured on the shaft 93, this shaft 93 is rotatably mounted in bearings 94 and 95 which are integral with the vertically disposed member 36.

Fixedly secured on the lower end of shaft 93 is a beveled gear 96 which meshes with a beveled gear 97, said beveled gear 97 being fixedly mounted on one end of traverse 98. Traverse 98 has its ends rotatably mounted in members 36 and 37, and has a suitable reversed groove cut therein which is engaged by one end of traverse 99. Traverse 99 is slidably mounted on bar 100, which bar has its ends secured also in vertically disposed members 36 and 37. Rotatably mounted in the left-hand end of traverse 99, (Fig. 4), is a plunger 101 which has a flattened lower end fitting into the groove in traverse 98 and since this member 101 has a flattened portion engaging the groove when it comes to one end of the reverse groove, the member is free to rotate and to

start the traverse travelling in the opposite direction on the rod 100. The right-hand portion of traverse 99, as seen in Figure 4, has pivotally mounted therein a thread guide 102 which projects upwardly and has an eyelet 103 in the upper end thereof through which the strand passes to the spool of yarn 94. A bar 104 supports the member 102 and prevents the clockwise rotation of thread guide 99 about the rod 100 and likewise has its ends fixedly secured in members 36 and 10 37.

It is seen in Figure 1 that as the traverse 98 is rotated that the thread guide 102 will be traversed back and forth due to the reverse groove in the traverse 98, and cause the yarn to be wound properly upon the spool of yarn 84. A strand of yarn 105 is fed to the apparatus through the bore 106 in the spindle 28.

From the spindle 28 the yarn passes through eyelets 107 which are mounted on fliers 21 and 14 and then goes into another bore 108 in the lower side of flier 14. From this bore the yarn passes through a vertically disposed bore 109 in the lower portion of spool rack 35 and upwardly to another eyelet 110 secured to the thread guide 102. From this point the yarn goes through the eyelet 103 in the upper end of the thread guide 102 and onto the cone of yarn 84.

For each revolution of fliers 14 and 21 the yarn 105 is given two turns twist. The first twist is given as the yarn leaves the drafting rollers to enter bore 106 and the second twist is given between bore 109 and eyelet 103. Since this apparatus provides two turn twist per revolution of the flier, the production is doubled because the 35 yarn can be passed from the drafting rolls twice as fast in the process of ring twisting where one turn twist is given per revolution of the ring traveler.

As the fliers 14 and 21 are rotated, the collar 54 and worm gear 55 are likewise rotated, thereby rotating the pinions 56 and 61 and the beveled gears 63 and 64. This will cause the shaft 65 with the worm gear 76 on the end thereof to likewise rotate which will, in turn, rotate the shaft 78, the beveled gears 81 and 82 to cause the roller 83 to rotate the tube of yarn 84 and to draw the thread thereon.

In the meantime, the beveled gear 92 will rotate the shaft 93 and cause beveled gears 96 and 97 to rotate traverse 98 and traverse the thread guide 96 to properly place the yarn on the tube. It is thus seen that means have been provided whereby the spool rack 35 can be held stationary at all times as the flier frames 14 and 21 rotate at a very high speed.

This is done by placing the top spindle on a different center from the bottom spindle and providing the locking device shown in Figures 4 and 5. This construction also allows the spool rack 60 and spindles to be operated in a vertical position instead of a horizontal position. When mounted in a horizontal position the spool rack has heretofore been held in stationary position by means of weights or gravity, which is not satisfactory 65 due to varying frictional forces in the bearings.

Since my apparatus winds and twists the yarn in one operation and is applicable to roving, spinning and twisting frames, the spooling operation is eliminated. The apparatus is applicable 70 to roving, spinning and twisting frames since it takes the yarn directly from the drafting rolls of these frames.

In the drawings and specification there has been set forth a preferred embodiment of the 75

invention, and although specific terms are employed, they are used in a generic and descriptive sense only and not for purposes of limitation, the scope of the invention being set forth in the appended claims.

5 I claim:

1. In a twisting and winding apparatus comprising a pair of rotary eccentric fliers driven in timed relation to each other, a spooling frame 10 mounted within said fliers and having one end supported by one of said fliers, a driven yarn receiving package mounted in the spooling frame, means connected to said spooling frame and engaging the other flier for holding the spooling frame stationary, and means for driving the yarn receiving package.

2. In a twisting and winding apparatus for textile fibers comprising a pair of rotary fliers having their respective axes of rotation eccentric, a resilient inter-connecting means between said fliers, a spooling frame mounted within said fliers and having one end supported by a flier, and having a driven yarn receiving package mounted therein, means connected to said spooling frame and engaging the center of the other of said fliers to hold the spooling frame stationary, and means for driving the yarn receiving package.

3. In an apparatus for twisting and winding 30 textile fibers comprising an upper and lower flier having opposed eccentric axes of rotation, a resilient inter-connecting means between said fliers, a spooling frame mounted within said fliers and supported by said lower flier, a driven yarn receiving package mounted in the spooling frame, means carried by the spooling frame for engaging the center of said upper flier to hold the spooling frame stationary, and means for driving the yarn receiving package.

4. In an apparatus for twisting and winding 40 textile fibers comprising an upper and lower flier having opposed eccentric axes of rotation, a resilient inter-connecting means between said fliers, a spooling frame mounted within said fliers and supported by said lower flier, a driven yarn receiving package mounted in the spooling frame, means carried by the spooling frame for engaging the center of said upper flier to hold the spooling frame in stationary position and an axial opening in the center of said upper flier for the passage of strands of yarn, a second axial opening in said lower flier to allow strands of yarn to pass to said spooling frame, and means for driving the yarn receiving package.

5. In a twisting and winding apparatus for 50 textile fibers comprising a pair of rotary fliers having their respective axes of rotation eccentric, a resilient inter-connecting means between said fliers, a spooling frame mounted within said fliers and having one end supported by a flier, a driven yarn receiving package mounted in the spooling frame, means connected to said spooling frame and engaging the center of the other of said fliers to hold the spooling frame stationary and an axial opening in the center of each of said fliers to allow the yarn to pass to said spooling frame, and means for driving the yarn receiving package.

6. In a twisting and winding apparatus for 60 textile fibers comprising a pair of rotary fliers having their respective axes of rotation eccentric, a resilient inter-connecting means between said fliers, a spooling frame mounted within said fliers and having one end supported by a flier, a driven yarn receiving package mounted in the

spooling frame, means connected to said spooling frame and engaging the center of the other of said fliers to hold the spooling frame stationary, an axial opening in the center of each of said fliers to allow the yarn to pass to said spooling frame, and means for rotating said fliers and means carried by said frame for receiving said twisted material and means for driving the yarn receiving package.

5

7. A combined twisting and spooling apparatus comprising a flier, a spooling apparatus around which the fliers rotate, a traversing mechanism for the spooling mechanism, means driven by the rotation of the fliers for driving the traversing mechanism, means on one end 10 of the flier for driving the same, off-center means associated with the upper end of the flier for driving the flier, a flexible connection between the flier and the off-center driving means and a connection between the off-center driving means 15 and the spooling mechanism for preventing rotation of the spooling mechanism when the flier is driven.

8. A combined twisting and spooling apparatus comprising a vertically disposed flier, means 20 secured to the lower end of the flier for imparting rotation thereto, off-center means flexibly secured to the upper end of the flier for driving the same, connections between said driving means and a common driving means, a spooling 25 mechanism mounted on the flier and around which the flier rotates, a connection between the off-center driving means and the upper end of the spooling mechanism, a traversing mechanism for the spooling mechanism, and means 30 driven by the flier for driving the traversing mechanism.

9. A twisting and winding apparatus comprising 35 a pair of fliers, a flexible connection between the fliers, one of the fliers being mounted eccentrically with relation to the other flier, means 40 for driving the fliers in timed relation with each other, a spooling apparatus disposed within a circle described by the rotation of said fliers, and supported concentrically to one of the fliers and eccentrically with relation to the other flier, a traversing mechanism for the spooling apparatus, means driven by one of the fliers for driving the traversing mechanism, and a connection between the spooling apparatus and the eccentric flier for preventing rotation of the spooling 45 apparatus.

10. In a twisting and winding apparatus for 50 textile fibers comprising a pair of rotary fliers having their respective axes of rotation eccentric, a resilient inter-connecting means between said fliers, a spooling frame mounted within said fliers and having one end supported by a flier, means connected to said spooling frame and engaging the center of the other of said fliers to hold the spooling frame stationary and a traversing mechanism for the spooling frame and means driven by one of the fliers for driving said traversing mechanism.

11. In an apparatus for twisting and winding 55 textile fibers comprising an upper and lower flier having opposed eccentric axes of rotation, a resilient inter-connecting means between said fliers, a spooling frame mounted within said fliers and supported by said lower flier, means carried by the spooling frame for engaging the center 60 of said upper flier to hold the spooling frame stationary and a traversing mechanism for the spooling frame and means driven by one of the fliers for driving said traversing mechanism.

75 FRANKLIN H. SHINN. 75
